MOLD FOR COMESTIBLES OR SIMILAR ARTICLE

Robert F. Bateman, North Smithfield, and James B. Swett, Barrington, R.I., assignors to Dart Industries, Inc., a corporation of Delaware

Continuation of design application Ser. No. 4,901, Dec. 2, 1966. This application Sept. 6, 1967, Ser. No. 8,838

Term of patent 14 years

Int. Cl. D7—02

U.S. Cl. D44—1

FIG. 2

This is a continuation of design application Ser. No. 4,901, filed Dec. 2, 1966.

FIGURE 1 is an exploded perspective view of a mold for comestibles or similar article showing our new design; and

FIGURE 2 is an assembled perspective view taken from the right of FIGURE 1.

The essential features of the design are shown in full lines.

We claim:

The ornamental design for a mold for comestibles or similar article, substantially as shown and described.
